UNITED STATES PATENT OFFICE.

THOMAS HUBERDEAU, OF LARIMORE, NORTH DAKOTA.

MEANS FOR FASTENING BOILER-TUBES.

SPECIFICATION forming part of Letters Patent No. 629,690, dated July 25, 1899.

Application filed April 4, 1899. Serial No. 711,675. (No model.)

To all whom it may concern:

Be it known that I, THOMAS HUBERDEAU, a citizen of the United States, residing at Larimore, in the county of Grand Forks and State 5 of North Dakota, have invented certain new and useful Improvements in Means for Fastening Boiler Tubes or Flues; and I do hereby declare the following to be a full, clear, and exact description of the invention, such as will 10 enable others skilled in the art to which it app pertains to make and use the same.

This invention relates to means for fastening boiler tubes and flues; and the purpose of the same is to make provision for the in 15 equality of expansion and contraction of the parts comprising the joints due to sudden changes and drafts, whereby leaking at the joints is obviated.

The invention consists of the construction 20 and arrangement of parts more fully herein after described and claimed.

In the accompanying drawings, Figure 1 is a perspective view of portions of opposite boiler-heads or flue-sheets, as the case may be, 25 showing the improved mode of fastening the tubes or the flues. Fig. 2 is a vertical longitudinal section of one of the tubes or flues, on an enlarged scale and better illustrating the relative position of the fastening means. Fig. 30 3 is a detail perspective view of one of the tubes or flues. Fig. 4 is a detail perspective view of one of the fastening devices.

Referring to the drawings, wherein similar numerals are utilized to indicate correspond 35 ing parts in the several views, the numeral 1 designates opposite heads or sheets and having openings 2 therein at regular intervals to receive the tubes or flues 3. The latter may be formed in any manner now well known, 40 with the exception of such features as are usually provided to facilitate beading, crimping, and flanging. The exterior of the opposite end portions of the flues or tubes are provided with screw-threads 4; but otherwise the 45 primal structure of the same remains normal and undisturbed.

The openings 2 are larger than the diameter of the tubes or flues, and to hold the latter in the heads or sheets 1 tubular fastenings 5 are 50 employed, each having a screw-threaded bore 6 and an outer flange 7, with a polygonal perimeter for engagement by a wrench or other

similar implement. Immediately next to the flange 7 a circumferential shoulder or enlargement 8 is formed on the fastening device and 55 is threaded, as at 9, and adapted to engage threads 10, which are formed in each instance in the walls of the openings 2. The unthreaded inner end portion of the tubular fastening is slightly less in diameter than the opening 60 2, so that it can be easily inserted in or withdrawn through the latter in the operations of 65 assembling or disconnecting the parts.

In connecting up the several parts the tubes or flues are inserted through the opposite 65 heads or sheets and the ends receive the tubular fastenings 5. When these latter are firmly screwed in place, the threaded portions 9 thereof snugly fit in the threaded openings 2, and the flanges 7 at opposite ends bear 70 against the outer sides of the said heads or sheets. By this means the tubes or flues are similarly set at opposite ends and being of the same thickness from end to end, and the fastenings in the main also being of the same 75 thickness the expansion and contraction will be equal, or nearly so. When the flues expand from the heat, they will remain firm in their securement, and when the cold air strikes both the flues and fastenings the 80 shrinkage, which occurs longitudinally, will cause the shoulders and flanges of the fastenings to be drawn tightly against the heads or sheets, but, owing to a similarity of material 85 and thickness of the portions of the device most affected, not so tight as to occasion any breaking of the said tubes or flues. Consequently a durable construction is provided 90 and also means for quickly assembling the parts of the boiler set forth and the use of expanding tools or implements is dispensed with entirely.

As shown, the extremities of the tubes or flues extend to near the outer face of the tube-sheet, but terminate within the fastenings a short distance from the outer ends of 95 the latter in order to prevent the cold air from striking the ends of the tubes first and chilling them to the extent of starting the joint between the parts 3 and 5 when the furnace-door is opened. By having the flues extend to near the outer face of the flue-sheet the weight of the flues and the strains exerted by 100 expansion and contraction are sustained by

both the sheet and fastening and not thrown entirely upon the latter, and by having the flues terminate short of the outer ends of the fastenings the cold air strikes the flanged 5 ends of the fastenings, which, being comparatively heavy, are not so readily susceptible to sudden changes of temperature and draft. The fastenings project beyond the inner faces 10 of the flue-sheets a distance to insure a firm and stable support and connection of the flues therewith, and in order that the fastenings may not become stuck by corrosion of the externally-threaded portions 8 the inner ends thereof are reduced and made plane- 15 surfaced, so that they may be readily withdrawn through the openings 2, while said threaded portions 8 are made equal in extent to the thickness of the flue-sheets, so as not to project beyond the inner face thereof and 20 so as to be protected as much as possible to prevent the deposit and incrustation of foreign matter thereon.

The proportions and dimensions of the several parts will be changed to accommodate 25 various applications without departing from the nature or spirit of the invention.

Having thus described the invention, what is claimed as new is—

1. A tubular fastening for boiler flues or 30 tubes having an internally-threaded bore, an outer external flange, a central externally-threaded portion, and an inner plane portion

of less diametrical extent than said externally-threaded portion, said parts being arranged and operating as in the manner and 35 for the purpose shown and described.

2. In a fastening for the ends of tubes and flues, the combination of a flue-sheet having a threaded opening, a fastening inserted in said opening and provided with an internally-threaded bore, an outer external flange abutting against the outer face of the sheet, a central externally-threaded portion engaging the threads of the opening in the flue-sheet and of a width or extent corresponding to the 45 thickness of said sheet so as to be protected thereby from the deposit and incrustation of foreign matter thereon, and an inner, plane portion of less diametrical extent than the said externally-threaded portion and projecting therefrom beyond the inner face of the flue-sheet, and a flue having a threaded end 50 screwed into the inner end of the threaded bore of the fastening to near the outer face of the flue-sheet and terminating short of the 55 outer end of the fastening, substantially as and for the purpose shown and described.

In testimony whereof I affix my signature in presence of two witnesses.

THOMAS HUBERDEAU. [L. S.]
